UNITED STATES PATENT OFFICE.

HATTIE M. PFALTZGRAFF, OF ATLANTIC CITY, NEW JERSEY.

SUPPORTER.

Application filed February 12, 1926. Serial No. 87,778.

My invention relates to belts or supporters utilizable for any of the known purposes to which structures of this character have been commonly applied, and for other desired 5 purposes.

In accordance with my invention, a supporter comprising an inner belt of suitable elastic or inelastic material and an outer inelastic belt, or equivalent, is provided with 10 one or more padded supports whereby pressure, variable at will, is applied to organs or parts of the body, and more particularly, the padded supports aforesaid are pressed or biased to operative position substantially 15 independently one of the other, preferably by a plurality of fastening devices or buckles co-operating with adjacent end sections of the belt or belts.

My invention resides in features and details of construction of the belt or supporter hereinafter described and claimed.

For an illustration of one of the various forms my invention may take, reference is to be had to the accompanying drawings 25 in which:

Fig. 1 is a front elevational view of a supporter embodying my invention.

Fig. 2 is a rear elevational view of the supporter shown in Fig. 1.

Fig. 3 is a horizontal sectional view of the supporter illustrated in Figs. 1 and 2.

Fig. 4 is a side elevational view of the supporter shown in Fig. 1.

Fig. 5 is a fragmentary horizontal sectional view taken on line 5—5 of Fig. 2.

Referring to the drawings, B is a main belt, preferably of elastic or semi-elastic knitted, porous, or equivalent, fabric of silk, silk and cotton, linen, cotton, or other desirable material. Preferably, belt B lies next to the body of the wearer and comprises two substantially duplicate sections a and b, adjacent spaced ends of which are connected to a reinforcing member c of cloth, or other suitable fabric of relatively heavy weight. If desired, member c may be provided with one or more elastic stays e disposed between layers of the fabric comprising said member and serving to further stiffen the same. A padded support f, preferably covered with material similar to that of belt B is carried by and usually corresponds generally in size with member c. It will be understood that the member c and support f may vary in size within considerable limits depending upon the condition

of the part of the body to which said support is applied.

In a region substantially diametrically opposite from reinforcing member c, the other adjacent ends of sections a and b terminate respectively in vertically extending strips g and h, preferably of inelastic cloth or equivalent fabric and reinforced, if desired, with one or more elastic stays i, Fig. 60 65 3. One of the strips aforesaid, as strip h, is suitably attached to a panel j, preferably formed from material generally similar to that of member c aforesaid, said panel normally bridging the space between sections a and b. Preferably, one or more elastic stays k embedded between layers of the fabric comprising panel j serve to add rigidity 70 75 and strength thereto. A padded support l, which may be variable in size as is support f but corresponding generally thereto, is secured preferably to the end of section b and also to the interior face of panel j and, accordingly, lies in a region substantially diametrically opposite from support f. 80

Belt B also comprises the hip extensions H integral therewith and extending below the hip over the thighs, forming in effect thigh straps integral with the seamless belt B. 85

An outer belt B¹ preferably of relatively heavy inelastic material comprises two substantially duplicate sections m and n, the former secured to belt B at its juncture point with strip g and the latter at the juncture point of belt B and strip h. Section m extends in one direction from the front of the wearer around one side and in the back terminates in two spaced straps o and p of inelastic material. Section n extends from the front of the wearer in an opposite direction from that taken by section m around the other side of belt B and in the back terminates in two spaced straps q and r corresponding with straps o and s. 90 95 100

Referring to Fig. 5, the strap o which is secured to the end of section m extends through a flattened ring or link s carried by the end of section n and is then folded back upon itself so as to lie upon the outer surface of section m. Strap p which is spaced from strap o a distance corresponding to the width thereof likewise extends through a flattened ring or link t, also carried by the end of section n in spaced relation with link s, Fig. 2. Strap p is also 105 110

folded back upon itself so as to lie upon the outer surface of section *m*.

Referring to Fig. 3, the strap *q* which is secured to the end of section *n* first passes through a flattened ring or link *u* secured by a flexible connecting device *v* to the reinforcing member *c*, then through another flattened ring or link *w* carried by the end of section *m* after which said strap is folded back upon itself so as to lie upon the outer surface of section *n*. Strap *r* which is spaced from strap *q* a distance corresponding to the width thereof lies between straps *o* and *p* and first passes through a flattened ring or link *x* secured by a flexible connecting device *y* to the reinforcing member *c*, then through another flattened ring or link *z* carried by the end of section *m* after which said strap is folded back upon itself so as to lie upon the outer surface of section *n*.

Referring to Fig. 2, straps *o* and *p* are shown as converging one toward the other and in the region occupied by one hip of the wearer are stitched, or otherwise suitably secured together, as indicated at *a*¹, Fig. 3, from whence a single strap *b*¹ extends toward the front of the supporter.

Still referring to Fig. 2, straps *q* and *r* are likewise shown as converging one toward the other and, in the region occupied by the opposite hip of the wearer, are stitched, or otherwise suitably secured together, as indicated at *c*¹, Fig. 4, from whence a single strap *d*¹ extends toward the front of the supporter. Straps *b*¹ and *d*¹ in the region occupied by the padded support *l* may be adjustably secured together in any suitable manner, as by the buckle or clasp *e*¹, Figs. 1 and 4.

It shall be understood that the mode of attachment of straps *o* and *p* to strap *b*¹ and straps *q* and *r* to strap *d*¹ may vary from that described above. For example, such straps may be connected together by utilizing a flat connecting ring as illustrated in my pending application, Serial No. 87,777, filed February 12, 1926, wherein a generally similar arrangement is illustrated. It shall be further understood that sections *m* and *n* of belt *B*¹ may be otherwise adjustably secured together in any desired region on reinforcing member *c* by structure or mechanism generally the equivalent of that described above.

As stated above, panel *j* is secured to strip *h*, in turn secured to the section *b* of belt *B*. Padded support *l* is also secured to panel *j* and said section *b* of the main belt. To the end that this portion of the belt structure may be adjustably secured to the adjacent portion of the belt structure comprising the section *a*, a corset lacing or other suitable arrangement may be utilized. However, as herein illustrated, I provide flexible connecting device *f*¹, Fig. 3, secured to a buckle *g*¹ comprising a strap-gripping member *h*¹ and

a snap member *i*¹, preferably of the character described and claimed in my co-pending application Serial No. 730,145, filed August 5, 1924. A substantially inelastic strap *j*¹ suitably secured to the free edge of strip *g* after passing beneath the gripping member *h*¹ of said buckle is folded back upon itself and then extended beneath a band *k*¹ carried by the section *m*. A flexible connecting device *l*¹ spaced from flexible connecting device *f*¹ and secured to the strip *h* supports a second buckle *g*² similar to that described above, said second buckle comprising a strap-gripping member *m*¹ and a snap member *n*¹. A substantially inelastic strap *o*¹ corresponding generally with strap *j*¹ is secured to the free edge of strip *g* and extends beneath the strap-gripping member *m*¹ of the buckle last described. Strap *o*¹ after passing beneath the band *k*¹ is stitched or otherwise suitably secured to the strap *j*¹, as indicated at *o*², Fig. 1.

Referring to Fig. 1, elastic or semi-elastic leg straps *P*¹ formed of some relatively soft material are detachably or otherwise suitably secured respectively to the sections *a* and *b* of belt *B*, preferably directly at the front of the wearer or in the region immediately below the strips *g* and *h*. At its other end, each leg strap is adjustably connected adjacent the hips of the wearer to the hip extensions *H* of belt *B* in any suitable manner, as by buckles *g*¹ carried by tabs *r*¹ secured to the respective hip extensions *H*.

The appliance herein described should be worn next to the skin and after opening the buckles *e*¹, *g*¹ and *g*² should be drawn on over the feet while the wearer is in a recumbent position. After the appliance has been placed in proper position, the leg straps *P*¹, *P*¹ are passed around the inside of the legs and respectively fastened to the buckles *g*¹. With the appliance thus in position, straps *j*¹ and *o*¹ are drawn through the buckles *g*¹ and *g*² thereby tightening sections *a* and *b* of belt *B*. When adjusted to the proper degree, the strap-gripping members *h*¹ and *m*¹ of buckles *g*¹ and *g*² are actuated to positively retain said straps in their adjusted positions by moving the extensions of said strap-gripping members into engagement with their respective snap members *i*¹ and *n*¹. Due to the fact that the horizontal portions of straps *j*¹ and *o*¹ are spaced one from the other in a substantially vertical plane, pressure is applied to the padded support *l* over a substantial area to force said support toward the body of the wearer. This result would not be attained if only one strap were utilized to tighten sections *a* and *b* of belt *B*.

Thereafter, when straps *b*¹ and *d*¹ are drawn toward the front of the wearer through the buckle *e*¹, sections *m* and *n* of outer belt *B*¹ will be tightened and the ends

thereof at the back of the wearer drawn into a position approaching or closely approaching one another. Due to the fact that at the back of the wearer, the straps b^1 and d^1 terminate in pairs of straps q and r and o and p , and since the ends of the straps comprising the respective pairs are secured to the free ends of sections m and n of outer belt B^1 , the pressure forcing the padded support f inwardly toward the body of the wearer will be applied over a substantial area, and the application of this pressure is not restricted such as would occur if but a single strap were utilized. In this tightening operation, sections m and n of outer belt B^1 draws the portion of the body of the wearer beneath said belt backwardly and rearwardly while at the same time padded support l is pressed inwardly. During continued tightening of straps b^1 and d^1 as aforesaid, inward movement of the padded support continues until the desired pressure is exerted over the vertebrae in the lumbar or sacral region. In this tightening operation the converging ends of straps q and r move toward the left, Fig. 2, whereby the end of section n of B^1 is moved toward the right. At the same time, the converging ends of straps o and p , Fig. 2, are moved toward the right whereby the end or section m of belt B^1 is moved toward the left. When the supporter is finally fixed in adjusted position, straps o , p and b^1 on one side of the wearer and straps q , r and d^1 on the other side of the wearer function as a further flexible support to hold the body of the wearer in proper position.

It will be observed that during the tightening operation described above, padded supports f and l are each initially biased or pressed toward the body of the wearer when straps j^1 and o^1 are drawn through buckles g^1 and g^2 to tighten belt B . Said supports are further biased in the same direction when straps b^1 and d^1 are tightened as described above to contract sections m and n of belt B^1 . It will be further observed that in each case the belt-tightening mechanisms proper are located outwardly of but immediately adjacent the respective padded supports. Due to this arrangement said supports are more effectively moved toward the body of the wearer than would be the case if the belt-tightening mechanisms proper were otherwise located.

Structure of the character herein described allows great freedom of movement of the body, nevertheless applying pressure thereto without undue exaggeration in any region even though the magnitude of the pressure is somewhat greater in the regions occupied by the abdomen and the vertebrae in the lumbar region.

The leg straps p^1 when secured in position as aforesaid, do not interfere with the free-

dom of movement of the legs with respect to the body and restrain the supporter from moving upwardly into an undesired position.

The integral extensions H upon the belt B closely embrace the thighs and assist in frictionally holding the entire structure in operative position upon the body.

What I claim is:

1. A supporter comprising an inner belt 75 adapted to extend substantially around the body of the wearer, a padded support secured to said belt at the back of the wearer, a second belt encircling said inner belt and opening at the back of the wearer, and means overlying said padded support for tightening said second belt.

2. A supporter comprising an inner belt 85 adapted to extend substantially around the body of the wearer, a padded support secured to said belt at the back of the wearer, a second belt encircling said inner belt and opening at the back of the wearer, and means comprising a plurality of spaced straps overlying said padded support for tightening said second belt. 90

3. A supporter comprising an inner belt 95 adapted to extend substantially around the body of the wearer, a padded support secured to said belt at the back of the wearer, a second belt encircling said inner belt and opening at the back of the wearer, and means for tightening said second belt comprising a plurality of straps secured to one end thereof, said straps extending toward the adjacent end of said second belt, thence loosely therethrough, and thence in reverse direction exteriorly of both belts. 100

4. A supporter comprising an inner belt 105 adapted to extend substantially around the body of the wearer, a padded support secured to said belt at the back of the wearer, a second belt encircling said inner belt and opening at the back of the wearer, and means comprising a plurality of vertically spaced straps for constricting said second belt, said straps terminating in elongated webs lying exteriorly of both belts and passing in opposite directions toward the front of the wearer. 110

5. A supporter comprising an inner belt 115 extending substantially around the body of the wearer and opening in the front, a padded support secured to said belt at the back of the wearer, an outer belt comprising two substantially duplicate sections, adjoining ends of which are secured at or adjacent the ends of said inner belt, means for tightening said inner belt, and adjustable means for moving the free ends of said outer belt toward each other whereby pressure is applied to said padded support for forcing the same toward the body of the wearer. 120

6. A supporter comprising an inner belt 125

- extending substantially around the body of the wearer and opening in the front, a padded support secured to said belt at the back of the wearer, an outer substantially inelastic belt comprising two substantially duplicate sections, adjoining ends of which are secured at or adjacent the ends of said inner belt, means for tightening said inner belt, and adjustable means comprising a plurality of vertically spaced straps for moving the free ends of said outer belt toward each other whereby pressure is applied to said padded support for forcing the same toward the body of the wearer.
- 15 7. A supporter comprising an inner belt extending substantially around the body of the wearer and opening in the front, a padded support secured to said belt at the back of the wearer, an outer substantially inelastic belt comprising two substantially duplicate sections, adjoining ends of which are secured at or adjacent the ends of said inner belt, means for tightening said inner belt, adjustable means comprising a plurality of vertically spaced straps for moving the free ends of said outer belt toward each other whereby pressure is applied to said padded support for forcing the same toward the body of the wearer, said straps terminating in elongated webs lying adjacent and outside of said sections and passing in opposite directions to the front of the wearer, and means for retaining said webs in adjusted position.
- 20 8. A supporter comprising an inner belt extending substantially around the body of the wearer and opening in the front, a plurality of padded supports secured individually to said inner belt substantially at the front and at the back of the wearer, an outer substantially inelastic belt comprising two substantially duplicate sections, adjoining ends of which are secured at or adjacent the ends of said inner belt, means for
- 25 tightening said inner belt in a plurality of vertically spaced regions, overlying one of said padded supports and adjustable means operative throughout substantially the width of said sections for tightening the same and for biasing another of said padded supports 50 toward the body of the wearer.
9. A supporter comprising an inner belt extending substantially around the body of the wearer, a padded support secured to said inner belt substantially at the back of the wearer, an outer substantially inelastic belt 55 extending around the body of the wearer and opening in the region occupied by said padded support, and means for tightening said outer belt in said region.
10. A supporter comprising an inner belt extending substantially around the body of the wearer, a padded support secured to said inner belt substantially at the back of the wearer, an outer substantially inelastic belt 60 extending around the body of the wearer and opening in the region occupied by said padded support, and means operative through substantially the width of said outer belt for tightening the same in said region.
11. A supporter comprising an inner belt extending substantially around the body of the wearer, a padded support secured to said inner belt substantially at the back of the wearer, an outer substantially inelastic belt 65 extending around the body of the wearer and opening in the region occupied by said padded support, and means comprising a plurality of vertically spaced straps operating outwardly of said support for tightening said outer belt.
12. A supporter comprising a main belt extending substantially around the body of the wearer and opening in the front, padded supports carried by said belt at the front and the back of the wearer, means for closing said belt to force one of said supports toward the body of the wearer, a substantially inelastic outer belt carried by said main belt, and means for constricting said outer belt 70 to force another support toward the body of the wearer.

HATTIE M. PFALTZGRAFF.
